(No Model.)

M. C. BARBER.
ROOFING TILE.

No. 599,312.

Patented Feb. 22, 1898.

UNITED STATES PATENT OFFICE.

MARSHALL C. BARBER, OF CANTON, OHIO.

ROOFING-TILE.

SPECIFICATION forming part of Letters Patent No. 599,312, dated February 22, 1898.

Application filed July 12, 1897. Serial No. 644,187. (No model.)

To all whom it may concern:

Be it known that I, MARSHALL C. BARBER, a citizen of the United States, residing at Canton, in the county of Stark and State of Ohio, 5 have invented certain new and useful Improvements in Roofing-Tiles; and I do hereby declare that the following is a full, clear, and exact description of the same, reference being had to the annexed drawings, making 10 a part of this specification, and to the letters of reference marked thereon, in which—

Figure 1 is a view showing a number of tile placed in position to form a roof. Fig. 2 is a detached view of one of the tiles. Fig. 3 is a 15 transverse section through line X X, Fig. 1. Fig. 4 is a view showing a portion of one of the roofing-tiles, showing the same in a different position from that shown in Fig. 2. Fig. 5 is a longitudinal section of the joint 20 or lap.

The present invention has relation to roofing-tiles; and it consists in the different parts and combination of parts hereinafter described, and particularly pointed out in the 25 claims.

Similar letters of reference indicate corresponding parts in all the figures of the drawings.

In the accompanying drawings, A represents the tile proper, which may be of any desired size, reference being had to convenience in manufacturing, burning, and applying the finished tile to a roof, which tile is provided with the convexo-concave portion *a*, which 30 portion is extended to produce substantially a semicircle in cross-section, and for the purpose of allowing the upper end or portion of the convexo-concave portion *a* to come under the lower end or portion of the next upper tile 35 40 said convexo-concave portions *a* are formed tapering, or, in other words, the diameter of the upper portion *a* should be less than the lower portion. To one side of the convexo-concave portion *a* extends the lateral plain 45 portion *b*, to which portion is joined or formed integral therewith the convexo-concave portions *c* and *d*, the portion *c* being formed of greater diameter than the portions *d*, as illustrated in the drawings.

50 For the purpose of providing a means for retaining a sufficient amount of cement to

connect the tiles together the upper sides of the convexo-concave portions *c* and *d* are each provided with the continuous cement-groove *e*, which is formed upon the upper side of the 55 rib or raised portion *f*.

For the purpose of providing a means for bringing the convexo-concave portions *a* into true alinement they are formed of such a size that the tiles can be moved laterally after 60 they have been placed over the portions *c* and *d*, as illustrated by the dotted lines, Fig. 3. By this arrangement the tiles can be placed in proper position without cutting or breaking 65 the tile.

In the placing of tile upon the roof-boards it is necessary that they be laid or placed in true alinement, and where it is necessary to bring this object about by the cutting and breaking of the tile many are damaged, thereby producing much waste; but by my peculiar arrangement I do away with the necessity 70 of reducing the size of the tile.

Another advantage by the peculiar formation of the tile herein shown is that should 75 any water find its way under the convexo-concave portions *a* it will be received against the convexo-concave portions *c* and *d* and carried toward the eaves of the building. I have described the portions *c* and *d* as convexo-concave; but, if desired, the portions *d* 80 may be and are preferably formed solid, which adds material and strength to the tile proper.

In use a row of tile is placed upon the roof-boards and secured at their upper ends by 85 nails in substantially the same manner that shingles are secured, after which another row is placed in position, and so on until the roof is completed, which gives it the appearance shown in Fig. 1.

90 For the purpose of allowing the tiles to fit down closely one upon the other at their proper places the cut-out portions *B* are provided, as illustrated in Fig. 4.

95 It will be understood that in use the cement is to be placed in the groove *e* while in a plastic state and in sufficient quantities to connect the portion of the tile coming directly above said groove, and after the tile has been set it is permitted to harden and thereby assist in securely holding the tile in proper fixed 100 position.

Having fully described my invention, what I claim as new, and desire to secure by Letters Patent, is—

1. As an improved article of manufacture, 5 a roofing-tile consisting of the tapered convexo-concave portion *a*, the lateral extension *b*, having formed integral therewith the portions *c*, and *d*, and the cement-rib *f*, provided with the groove *e*, all arranged substantially 10 as and for the purpose specified.
2. In a roofing-tile, the tile *A*, provided with a convexo-concave portion, the flat lateral portion *b*, the convexo-concave portion *c*, and the portion or rib *d*, formed smaller in cross- 15 section than the portion *c*, and the cement-groove, substantially as and for the purpose specified.

3. As an improved article of manufacture, a roofing-tile provided with the convexo-concave portion *a*, extended to form substantially 20 a semicircle, a flat lateral portion extended from the convexo-concave portion *a*, and provided with the curved portions *c*, and *d*, said portions being of different sizes in cross-section and of less diameter than the diameter 25 of the curved portion *a*, substantially as and for the purpose specified.

In testimony that I claim the above I have hereunto subscribed my name in the presence of two witnesses.

MARSHALL C. BARBER.

Witnesses:

J. A. JEFFERS,
F. W. BOND.
